UNITED STATES PATENT OFFICE.

RALPH B. COOLEY, OF GRANVILLE, MASSACHUSETTS.

DESIGN FOR A DRUM.

SPECIFICATION forming part of Design No. 26,082, dated September 22, 1896.

Application filed May 8, 1896. Serial No. 590,780. Term of patent 3½ years.

To all whom it may concern:

Be it known that I, RALPH B. COOLEY, a citizen of the United States, residing in Granville, Hampden county, State of Massachusetts, have invented and produced a new and original Design for Drums, of which the following is a specification.

The leading feature of my design is a drum of a general cylindrical shape banded with 10 end bands and an intermediate body-band, the said body-band being ornamented by stars of substantially the extent of the width of the said body-band with rays radiating therefrom, the said body-band being of a color 15 contrasting with the color or colors of the star and rays, and the said rays of individual stars extending into near proximity to the rays of adjacent stars.

In the accompanying drawing a drum embodying my design is illustrated. In this drawing the drum is shown as of a general

cylindrical form. The middle portion of the drum presents the appearance of a broad body-band A, ornamented with stars B and rays *a*, the said band being of a color or shade 25 contrasting with the color or shade of the said stars and rays.

C are end bands, which adjoin the band A. Crossing the band A are diagonal bands or lines D.

What I claim is—

The design for a drum and its ornamentation, substantially as herein shown and described, to wit, a drum substantially as shown and described, ornamented on the body-band 35 with stars with radiating rays substantially as described and shown in the accompanying drawing.

RALPH B. COOLEY.
